UNITED STATES PATENT OFFICE.

JOHN D. BRADY, OF EL DORADO, ARKANSAS.

DOUBLE-ACTING PUMP.

Application filed September 21, 1922. Serial No. 589,531.

To all whom it may concern:

Be it known that I, JOHN D. BRADY, a citizen of the United States, residing at El Dorado, in the county of Union and State of Arkansas, have invented an Improved Double-Acting Pump, of which the following is a specification.

This invention relates to mechanism for lifting a liquid, as oil or water, from deep wells. Such wells are usually drilled to a substantial depth, cased to prevent seepage and caving of the walls, further drilled of smaller diameter through such casing until near the desired stratum, a second string of pipe inserted to case the hole from bottom to top, and drilling continued into the desired stratum or pay sand. From the last drilled, uncased portion of the well, fluid may be drawn to the surface through a pipe having attached to the lower end thereof a pumping barrel and cooperating parts embodying my improvements.

Primary objects of my invention are to increase the efficiency of pumping apparatus by providing for the introduction of liquid to the barrel of the pump both above and below the reciprocating valve so as to secure the discharge of liquid at the top of the well on both strokes and substantially increase the amount of liquid delivered; to decrease the churning action of the pumping mechanism which commonly causes the production of "B. S.", and to minimize the difficulties commonly experienced from sand or grit settling around the cups of the traveling valve mechanism and troubles due to valves being held open by gas.

My invention is characterized by a working barrel having means for trapping there-in fluid on opposite sides of a reciprocable piston, in combination with a discharge tube, and valve mechanism for connecting said tube with said barrel on opposite sides of the piston alternately whereby liquid is delivered from the barrel to the tube upon each stroke and is discharged from the well upon each stroke, the discharge tube preferably supporting and effecting the operation of the piston and valve mechanism.

The characteristic features of my invention will more fully appear from the following description of a preferred embodiment thereof and the accompanying drawings in illustration of the same.

In the accompanying drawings, Fig. 1 is

a diagrammatic illustration of a deep well having inserted therein apparatus embodying my invention; Fig. 2 is a longitudinal sectional view of my improved pumping mechanism; Fig. 3 is an enlarged longitudinal sectional view through the valve mechanism fixed to the lower end of a tube by which such valve mechanism is operated and through which liquid is lifted; Fig. 4 is an enlarged vertical sectional view of the valve by which fluid is admitted to and trapped in the upper part of the working barrel; Fig. 5 is a sectional view taken on the line 5—5^x of Fig. 4; Fig. 6 is a sectional view taken on the line 6—6^x of Fig. 4; Fig. 7 is a sectional view taken on the line 7—7^x of Fig. 3; and Fig. 8 is a sectional view taken on the line 8—8^x of Fig. 3.

In the drawings there is shown a well having an enlarged upper section lined with the casing A, a smaller median section lined with the casing B extending to the top of the well, and the smaller lower section C which is not cased.

A string of tubing 1, anchored at the top of the well, has connected with the lower end thereof a barrel of slightly smaller internal diameter than the internal diameter of the tubing and comprising the sections 2 and 3 connected by the cylindrical valve body 4. The valve casing 4 contains the ports or passages 5 controlled by the ball checks 6 permitting passage of fluid from the well into the barrel, and preventing reverse flow, and a valve 7 fixed to the bottom of the barrel and controlled by the ball check 8 permits flow of fluid from the well into the lower part of the barrel and prevents reverse flow.

The top of the barrel is sealed by a packer valve 9 provided with cups 10, the top of the packer being of such diameter as to pass through the casing 1 but engage the top of the working barrel.

A string of sucker rods 11, reciprocable in the tubing 1, has secured thereto a valve casing 12 from which depends a tube 13 whose outlet is controlled by a ball check 14. The tube 13 extends through the packer valve 9 and cups 10 into the barrel and has fixed thereto the packing cups 15 engaging the inner surface of a small barrel 16 fixed to the top of the packer 9, whereby the return to the working barrel 2, 3 of fluid discharged to the tubing 1 from the tube 13 is prevented.

To the lower end of the tube 13 is secured a valve mechanism 16' into which is screwed the tube 17 having tubular packing cups 18 clamped in place thereon by nuts 14', thereby forming a piston reciprocable in the barrel to draw fluid into the chambers formed in the opposite ends thereof and force the trapped fluid into the tube 13 through the valve mechanism 16'.

10 This valve mechanism comprises a housing 18' containing a chamber 19 communicating with the barrel below the piston through the tube 17 and port 20 controlled by a ball check 21 and discharging through 15 the axial passages or ports 22; and a second chamber 23 separated from the chamber 19 by the diaphragm 24, communicating with the barrel above the piston through the radial passages or ports 25 and discharging 20 through the port 26. A second housing 27 is screwed on the threaded boss 28 of the housing 18' and is provided with a seat 29 for a ball check 30 for controlling communication between the chamber 23 and the passage 31 in the housing 27 which communicates through the coupling 32 with the tube 13. A pin 33 across the passage 31 prevents the ejection of the ball check 30 therefrom. Axial passages 22' in the housing 27 register with the ports 22 to permit discharge 30 from the chamber 19 to the coupling 32 and tube 13.

It will be understood that in the installation of my apparatus, the barrel, with the 35 valve mechanisms 4 and 7 attached thereto, is connected with the tubing 1 before it is lowered into the well. When the barrel has reached the proper depth, the tubing 1 is anchored at the top of the well, and the 40 top closure for the barrel and reciprocatory parts of the pump are lowered together on the end of a string of sucker rods. When the packing 9 and 10 is seated in the top of the barrel, the piston and valve mechanism 16' is lowered to working position and reciprocated through the reciprocation of the sucker rods.

On the down stroke of the piston, fluid which has entered the barrel through the 50 valve 7 is forced through the tube 17 past the valve 21, through the chamber 19, axial passages 22, 22', coupling 32, tube 13, valve 12, into the tubing 1; the valve 30 remaining seated during this operation to prevent 55 discharge of fluid through the ports 25 to the barrel above the piston. During the downward stroke of the piston, the valve 8 remains seated to prevent escape of fluid from the barrel to the well, while the valves 60 6 are unseated and liquid is drawn by suction from the well into the barrel above the piston.

Upon the up stroke of the piston, the valve 8 is unseated to admit fluid to the 65 barrel below the piston, and the valves 5

are seated to prevent return flow to the well of fluid in the barrel above the piston, such fluid being forced through the radial ports 25, chamber 23, past the valve 30, through the passage 31, coupling 32, tube 13, past the valve 14, into the tubing 1, from which a substantially continuous stream is discharged.

Having described my invention, I claim:—

1. In a pump, the combination with a barrel, of a piston having a passage therethrough, a valve housing fixed to said piston at its upper end and adapted to communicate with said passage, a valve carried by said housing for preventing reverse flow through said piston, a second valve housing fixed to said housing first named, a valve for controlling the flow from said housing second named, one or more passages connecting said housings around said valve second named, one or more passages connecting said housing second named with said barrel, a tube fixed to and communicating with said housing second named, and a non-return valve carried by said tube to prevent reverse flow therethrough to said housing second named.

2. In a pump mechanism a hollow piston having an upper screw threaded end, a valve housing detachably connected to said screw threaded end and providing a chamber therein and a valve seat, a valve resting by gravity on said valve seat within said chamber, said housing providing passageways extending upwardly therethrough from said chamber and providing an upper screw threaded extension having a second chamber, said housing having ducts radially extending from the outside portion of said housing to said second chamber, and a second housing upwardly carried by the screw threaded extension at the top of said first mentioned housing providing a chamber therein and a valve seat, a valve resting by gravity on said valve seat, said second housing having passageways upwardly therein adapted to align with the first mentioned passageways of said first mentioned housing to communicate the chamber of said second mentioned housing with the first mentioned chamber of said first mentioned housing.

3. In a well pump the combination of a working barrel, valve means for admitting liquid from exterior of the barrel to the barrel at a certain level and preventing return flow of the liquid from the barrel, a second valve means above the first mentioned valve means for admitting a liquid from the exterior of the barrel to the barrel and preventing return flow of the liquid from the barrel, a hollow tube reciprocable in the barrel, a closure in the barrel above the second mentioned valve means and thru which the tube passes in a liquid sealed con-

nection for reciprocation, piston means carried by the tube above the closure, a non-return valve cooperating over the outlet end at the top of said tube above said piston

the tube to act in order to admit liquid to the tube and force it upwardly in the tube to the non-return valve at the top of said tube.

means, and valve means carried by the tube between the first and second mentioned valve means adapted upon each stroke of

In testimony whereof I have hereunto set my name this 16th day of September, 1922.

JOHN D. BRADY.
